DESIGN FOR AN IGNITION GENERATOR

Edward A. Vogel, Beloit, Wis., assignor to Fairbanks, Morse & Co., Chicago, Ill., a corporation of Illinois

Application March 17, 1941, Serial No. 99,645

Term of patent 7 years

To whom it may concern:

Be it known that I, Edward A. Vogel, a citizen of the United States, residing in the city of Beloit, county of Rock, State of Wisconsin, have invented a new, original, and ornamental Design for an Ignition Generator, of which the following is a specification, reference being had to the accompanying drawing, forming a part thereof.

In the drawing:

Fig. 1 is a top plan view of the ignition generator showing my new design; Fig. 2 is a side elevational view thereof; Fig. 3 is a bottom plan view thereof; Fig. 4 is an end elevational view at the distributor end of the ignition generator, and Fig. 5 is an end elevational view of the opposite end of the ignition generator. The side of the ignition generator opposite that shown in Fig. 2 is the same as the side shown except that the resistance plate element is omitted.

I claim:

The ornamental design for an ignition generator, substantially as shown and described.

EDWARD A. VOGEL.
